UNITED STATES PATENT OFFICE.

JOHN THOMA, JR., OF MEDINA, NEW YORK.

WASHABLE SLIPPER.

1,286,446.

Specification of Letters Patent.

Patented Dec. 3, 1918.

Application filed April 3, 1918. Serial No. 226,538.

To all whom it may concern:

Be it known that I, JOHN THOMA, Jr., a citizen of the United States of America, residing at Medina, in the county of Orleans 5 and State of New York, have invented certain new and useful Improvements in Washable Slippers, of which the following is a specification.

The primary object of the invention is 10 the provision of a slipper arranged with a removable stiffening sole whereby the remainder of the slipper may be readily washed when said stiffener is removed although the slipper will have a firm sole support for the foot when the device is assembled.

A further object of the invention is the provision of a carrying means for a stiffener arranged in connection with the inner sole 20 whereby the inner sole and stiffener are flatly maintained entirely within the slipper upon the outer sole thereof when the device is assembled, the inner sole and stiffener being separable from the outer sole upon flexing 25 while the stiffener is detachable from the inner sole upon bending in an opposite direction.

A still further object of the device is to 30 provide a slipper of washable material adapted for detachably mounting a stiffener upon the inner sole thereof and having a retaining connection with the inner face of the outer sole of the slipper whereby the stiffener may be readily separated from the slipper upon slightly flexing in opposite directions and without abruptly bending or cracking the stiffener.

With these general objects in view and others that will appear as the nature of the 40 invention is better understood, the same consists in the novel construction, combination and arrangement of parts hereinafter fully described, illustrated in the accompanying drawing and pointed out in the appended 45 claims.

In the drawing forming a part of this application and in which like numerals refer to corresponding parts throughout the several views,

50 Figure 1 is a perspective view of the device with the inner sole and its stiffener bent outwardly of the slipper as positioned during the assembling or disassembling operation of the stiffener with the inner sole;

55 Fig. 2 is a central longitudinal sectional

view of the device in its complete assembled arrangement;

Fig. 3 illustrates a step in the assembling or disassembling of the outer sole with the inner sole and stiffener; and

Fig. 4 is a plan view of the heel portion of the stiffener.

Referring more in detail to the drawing, my invention is illustrated in connection with a form of slipper 10 of the usual form 65 in which a counterportion is omitted but it will be understood that the device is also serviceable in connection with a slipper or a shoe of different form and with or without a counter and upper portion.

The slipper 10 provides an outer sole 11 having a toe-covering or portion 12 secured to the outer edge thereof while an inner sole 13 is marginally secured to the edges of the outer sole 11 and toe-covering 12 for forming a pocket adapted for the removable reception of a suitable stiffener 14. All portions of the slipper are formed of washable material excepting the stiffener 14 which is formed of such material as fabric board, or 80 other flexible sheet material.

The inner sole 13 is separated from the outer sole 11 throughout the entire heel and instep portions of the inner sole being only secured thereto at its toe portion, the connection being indicated as far as the points 15 at opposite sides of the toe portion of the slipper lying within the toe-covering portion 12 thereof. A pocket 16 is formed upon the under side of the heel portion of the inner sole 13 adapted for receiving the heel portion 17 of the stiffener 14 when the toe portion of the stiffener is arranged within the pocket formed between the toe portions of the said outer and inner soles.

By referring to Fig. 1 of the drawing, it will be understood that upon flexing the stiffener 14 in the manner therein shown, the heel portion of the stiffener 14 may be readily withdrawn from or inserted within the heel pocket 16 of the inner sole 13. A suitable binding 18 is preferably arranged around the free edge portion of the inner sole 13 extending between the two opposite points 15 of the slipper and also binding the outer edges of the pocket 16.

A flap 19 is secured upon the inner face of the heel portion of the outer sole 11 beneath which flap 19, the heel portion of the inner sole 13 with the stiffener 14 attached thereto

is adapted to be projected and withdrawn upon flexing the stiffener 14 in the manner indicated in Fig. 3 of the drawing. A binding 20 extends entirely around the outer sole 11 and overlies the outer edges of the flap 19.

The stiffener 14 being formed of flexible material which will readily bend without breaking is readily attached in this manner to the inner sole 13 and the heel portion of the inner sole readily positioned beneath the flap 19 of the outer sole 11 when the slipper is ready to wear as shown in Fig. 2 of the drawing. When it is desired to remove the stiffener 14 to wash the slipper, the stiffener and inner sole are bent substantially centrally at the unattached edge portion of the inner sole 13 being bent outwardly between the points 15 of the slipper and the inner end or mouth edge 21 of the flap 19, such withdrawing operation being indicated in Fig. 3 of the drawing while it will be understood that a reassembling of the device is accomplished by reversing this operation.

25 The Arthur Hale patents are well known to this applicant and such structures are not broadly claimed but what my invention does cover is the substantially locking of a removable stiffener in place by inserting the heel end of the inner sole and stiffener within the heel flap of the outer sole entirely inside of the slipper and taken together with the structure which renders the insertion and removal of the stiffener 14 an easy operation 30 due to the rear movable portion of the inner sole 13 between its points of attachment 15 with the outer sole and the adjacent edge 21 of the receiving flap 19. The stiffener 14 is substantially of the same length as the inner sole 13 and slightly stretches the inner sole during the assembled operation so that the inner sole is maintained in stretched relations upon the outer sole 11 when positioned for use and with the stiffener 14 35 maintaining the inner sole smooth and unwrinkled as well as affording a stiffened support for the foot of the wearer.

40 What I claim as new is:—

1. A washable slipper comprising an outer sole and a toe-covering portion, an inner sole having its toe portion marginally attached to the outer sole within the toe-covering portion and providing a free heel and instep portion for the inner sole, an inwardly opening pocket upon the under side of the heel portion of the inner sole adapted for the reception of the heel portion of a stiffener when arranged between the inner and outer soles, and a flap upon the inner 45 side of the heel portion of the outer sole

5 having an unattached inner edge serving as a mouth portion adapted for the reception of said heel portion of the inner sole for positioning the same beneath the said flap flatly arranged upon the outer sole.

65

2. A washable slipper comprising an outer sole and a toe-covering with an inner sole marginally secured within said toe-covering and being substantially of the same length as the outer sole, receiving pockets upon the adjacent inner faces of the heel portions of both of said soles, and a stiffener adapted for arrangement between said inner and outer soles with the heel portion thereof within both of said pockets when the slipper is arranged for use.

70

3. A washable slipper comprising an outer sole and a toe-covering carried thereby, an inner sole having its toe portion secured to the edges of the outer sole with unattached free instep and heel portions, a pocket upon the lower face of the heel portion of the inner sole, and a flap upon the inner face of the heel portion of the outer sole terminating short of the instep portion of the slipper and adapted for the reception of the heel portion of the inner sole when the device is assembled.

80

4. A washable slipper comprising an outer sole and a toe-covering carried thereby, an inner sole having its toe portion secured to the edges of the outer sole with unattached free instep and heel portions, a pocket upon the lower face of the heel portion of the inner sole, and a flap upon the inner face of the heel portion of the outer sole terminating short of the instep portion of the slipper, a flexible stiffener positioned between the toe portions of said inner and outer soles with the heel portion of the stiffener 90 removably arranged within the pocket of the inner sole, the heel portion of the stiffener and inner sole together with said pocket being adapted for arrangement beneath the said flap between the flap and the heel portion of the outer sole when the slipper is arranged for use with the inner sole in smooth 95 stretched relations upon said stiffener.

100

5. A washable slipper comprising an outer sole and toe covering, an inner sole having a marginal portion thereof attached to the outer sole, receiving pockets upon the adjacent end faces of the unattached portions of both of said soles, and a stiffener adapted for arrangement between said inner and outer soles with an end portion thereof within both of said pockets when the slipper is arranged for use.

110

In testimony whereof I affix my signature.
JOHN THOMA, JR.
